UNITED STATES PATENT OFFICE

FREDERICK J. HENRY, OF TAUNTON, MASSACHUSETTS

CLAMPING ADJUNCT FOR COAT HANGERS

Application filed July 30, 1928. Serial No. 296,312.

The object of this invention is to provide an adjunct readily engageable with and removable from the neck portion of an ordinary wire coat hanger, the neck portion being the brace which extends between the shoulder portions of the hanger, the function of the adjunct being to clamp a garment such as a pair of trousers or a folded dress skirt against the hanger neck so that a wire coat hanger may be adapted by the adjunct to support a garment in addition to a coat.

Of the accompanying drawings forming a part of this application,

Figure 1 is a perspective view showing a common form of coat hanger and an adjunct embodying the invention engaged with the hanger neck and clamping the legs of a pair of trousers against the neck.

Figure 2 is an enlarged fragmentary section on line 2—2 of Figure 1.

Figure 3 is an enlarged fragmentary section on line 3—3 of Figure 1.

Figure 4 is a side view showing the adjunct separately.

Figures 5 and 6 are end views looking toward opposite ends of the adjunct.

The same reference characters indicate the same parts in all of the figures.

In the drawings, 12 designates the neck portion, and 13, 13 the shoulder portions of a well known wire coat hanger.

The adjunct embodying my invention is composed of a wire rod, preferably of the same gage as the wire of which the hanger is made, and including a straight elongated jaw 14, and hooks formed on the ends of said jaw and both projecting from one side thereof.

To distinguish the hooks from each other, I call one a primary hook and the other a secondary hook.

The primary hook includes an inner arm 15, projecting laterally from one end of the jaw 14, a neck 15a offset by the inner arm from the jaw, and an outer arm 15b extending beside the arm 15, to form an open hook.

The secondary hook includes an arm 16, projecting laterally from the opposite end of the jaw 14, a neck 16a offset by the inner arm from the jaw 14, and an outer arm 16b ex-

tending beside the inner arm 16 to form an open hook, the outer arm being preferably parallel with the inner arm, as best shown by Figure 4.

When the garment is clamped, it exerts 55 yielding pressure on the adjunct, so that the necks 15a and 16a are confined against the hanger neck, the yielding pressure permitting the disengagement of the hooks from the neck, preparatory to the removal of the garment.

Figures 1, 2 and 3 show the legs of a pair of trousers clamped by the jaw 14 against the neck 12.

It is obvious that a folded skirt or other 65 garment may be thus clamped.

The hooks are proportioned to maintain the jaw 14 substantially parallel with the hanger neck 12, as shown by Figure 1, and at a clamping distance therefrom, as shown by 70 Figures 2 and 3. By clamping distance, I mean that the jaw 14 is so spaced from the neck 12, that garment portions interposed between the jaw and neck are prevented thereby from slipping downward when the 75 hanger is operatively supported and the garment depends from the hanger.

The separability of the adjunct from the hanger neck permits the unobstructed application of a garment to one side of the neck, 80 before the adjunct is engaged therewith, so that the garment may be conveniently applied in a predetermined position to the neck, and then clamped between the neck by the jaw 14, when the hooks are engaged with the neck. 85

I claim:

The combination with a wire coat hanger including garment shoulder-supporting portions and a neck connecting the same, of a clamping adjunct composed of a wire rod including an elongated clamping jaw and U-shaped open hooks projecting laterally in the same direction from opposite ends of the jaw, said hooks being separately engageable with the hanger neck, so that the adjunct is 90 separable from the hanger, the hanger hooks being proportioned to maintain the jaw substantially parallel with the neck and at a clamping distance therefrom when they are 95 engaged with the neck, the separability of 100

the adjunct permitting the unobstructed application of a garment to one side of the neck, the arrangement being such that the applied garment may be clamped by the jaw against the neck by the engagement of the hooks therewith, so that when the hanger is operatively supported, the garment depends therefrom.

In testimony whereof I have affixed my
10 signature.

FREDERICK J. HENRY.
